APPARATUS FOR MAKING STRINGS

Harold W. Roberts, La Grange, Ill., assignor to
Thompson Manufacturing Company, Chicago,
Ill., a corporation of Illinois

Application March 11, 1940, Serial No. 323,321

15 Claims. (Cl. 57—25)

This invention relates in general to the method of twisting gut strings for tennis, badminton and the like, and has more particular reference to a new and improved apparatus and method for twisting a plurality of plies in one direction at one end of a string, and twisting all of the plies together by rotating them at the other end of the string.

Among the objects to be attained in carrying out and utilizing this new and improved process and apparatus are:

To produce plies of the same diameter, the same length and under the same tension when twisting;

To cause the plies to take a definite position in the string and to pull toward the center thereof;

To reduce the total diameter and thus to offer a narrow section to outside abrasive action;

To change a flat ribbon to a round string in making up the plies;

To allow the use of a core of this material;

To eliminate the necessity of closely watching the ply length and tension in making strings; and

To definitely mark or identify a string product; and

In general to produce the structure and to employ the novel method herein shown and described in making gut strings.

In the accompanying drawings illustrating a preferred embodiment of the mechanism used in carrying out this improved process,

Fig. 1 is a side view illustrating the ply twisting head at one end and the rotator at the other end of a string;

Figs. 2 and 3 are sectional and side views illustrating the structure of the string gripper;

Fig. 4 is an end view of the gripper;

Fig. 5 is a face elevation of the twisting head; and

Fig. 6 is a side elevation of the twisting head.

At present gut strings are made from ribbons obtained by slitting casings from end to end. These ribbons vary in width from $\frac{1}{4}$ to $\frac{3}{4}$ of an inch and in thickness from .002 to .006 when dry. Even though they are selected for size and grouped for width of ply as closely as practical there are great variations within each string. A sufficient number of ribbons are tied together on a loop at one end to make a completed string of the desired gauge. At the other end the ribbons are loose, they are put on a hanging bench, straightened out, and an attempt is made to get the same tension on each ply before the loop is placed on the opposite end at the required posi-

tion to produce a string of the desired length. This produces a group of loose plies of supposedly the same length fastened to loops at each end.

5 In the condition thus assembled the plies go through considerable processing, including drying, before any twisting takes place. Even assuming that the plies are of equal length and under the same tension at the time they are hung, further processing affects each ply differently; some shrink and others stretch, so that at the end of the processing when they are ready to be twisted the plies are not of uniform length and will not twist under uniform tension. The slack in some plies is taken up by the twisting before any revolutions are made in the string, which by no means produces the desired equal length and equal tension on each ply. One end loop is placed on a spinning hook and the other end is held stationary and as rotations are continued the string is twisted, allowing the plies to take any position they will until the string has the desired amount of twist to produce a round gut string when dry.

15 A suitable apparatus and mechanism for practicing this method comprises a motor driven hook or loop for attachment at one end of a string and a rotatable head with a plurality of grippers for separately engaging the ribbons at the other end of the string. The mechanism is so arranged that it is possible to rotate the ribbons in one direction, and to rotate all of the ribbons from the other end of the string in a reverse direction. Improved means is also provided for attaching the ribbons, rotating the separate plies, and releasing the plies when the string twisting is completed.

20 25 30 35 40 45 50 A suitable apparatus and mechanism for practicing this method comprises a motor driven hook or loop for attachment at one end of a string and a rotatable head with a plurality of grippers for separately engaging the ribbons at the other end of the string. The mechanism is so arranged that it is possible to rotate the ribbons in one direction, and to rotate all of the ribbons from the other end of the string in a reverse direction. Improved means is also provided for attaching the ribbons, rotating the separate plies, and releasing the plies when the string twisting is completed.

Plies and ribbons are synonymous terms, each individual ribbon or ply is twisted anti-clockwise and then sufficient ribbons or plies to make a string of desired gauge are grouped together and twisted into a single string.

Referring now more particularly to the drawings, a string ready to be twisted is represented in Fig. 1 as consisting of a plurality of plies 10 arranged in the form of an elongated cone and connected at one end to a loop or hook 11 operated by means of a shaft 12 connected to a motor 13 mounted at one end of a bench or other suitable support 14.

45 50 55 At the base of the cone the plies are connected to a number of grippers 15 mounted in a spinning head 16 at the other end of the bench and actuated for spinning movement by a connected motor 17. The motors 13 and 17 are conveniently

controlled by electrical connections (not shown) and switches 18 and 19 adjacent the twisting head.

The twisting head comprises a circular disc 20 having an outer flange 21 and teeth 22 corresponding in number with a plurality of spaced perforations 23 for receiving the grippers 15.

A hub 24 of the disc is rotatable about a bearing sleeve 25 extending from a bearing 26 formed as a part of a supporting base or upright standard 27. Rotatable within the sleeve is a driving shaft 28 with a bearing 29 between it and the sleeve at the disc end and having a gear 30 secured to it at the other end beyond the bearing portion 26. Meshing with the gear 30 is a driving pinion 31 secured to a shaft 32 having fast and loose pulleys 33 and 34 thereon, the former being driven by a belt 35 from the driving pulley of motor 17.

One of the grippers 15 is rotatably mounted in a bearing 36 in each of the outer perforations 23 of the disc 20. Each gripper comprises a sleeve 37 having a pinion 38 secured to or formed integral therewith and projecting from the sleeve intermediate the ends thereof. Near one end the sleeve has a recess 39 with a bayonet slot 40 at its inner end, and a slot 41 at its outer end extending to the extremity of the sleeve. The interior recess 42 at this end of the sleeve is beveled to receive a correspondingly beveled tip 43 of a gripper rod 44 movable in the bar having a larger portion 45 fitting loosely in the opening of the sleeve and substantially traversing the recess 39. A stud 46 projects from the outer end of the enlarged portion and is adapted to be seated and engaged by the bayonet slot 40 against the tension of a spring 47 located in the space between the interior of the sleeve 37 and a reduced portion 48 of the rod, bearing against the enlarged portion 35 at one end and against a small collar 49 in the end of the sleeve at the other end, held in place by a set screw 50, the collar also serving as a bearing for this end of the rod 44. At this end of the rod and spaced from the end of the sleeve is a projecting collar or head 51 for moving the rod against the tension of the spring 47 as hereinafter set forth.

The tapered end 43 of the rod is forced into the correspondingly tapered recess 42 of the sleeve by the spring 47 but the slot 41 extends from the edge of the sleeve to the central opening at the end thereof so that the flat gut ribbons for forming the plies, or the plies themselves, may be readily inserted through the slot 41 when the rod is held back against the spring 47 and the inner edges 52 of the recess 39 near the end of the sleeve are rounded to receive and allow the extremities of the gut ribbons or plies to extend therefrom without tending to cut them. If it is necessary to maintain the gripper rod in retracted position for any length of time it may be moved against the spring 47, seating the stud 46 in bayonet slot 40 where it will be held until released by a slight rotation of the rod.

Secured to the shaft 28 by a fastening nut 53 or other suitable means is a gear having a hub portion 54 and a ring gear 55 engaging all of the gripper gears 38. This gear is seated in a recess formed by the flange 21 of the disc 20 and is enclosed by a face plate 56 secured to the flange and having bearings 57 therein surrounding each one of the gripper sleeves 37 for holding the gripper in place and for common rotation of all of the grippers by means of the gear 55.

In order to bring each gripper successively into

place for attaching the ribbons or plies thereto the disc 20 is rotated step by step by means of the teeth 22. This may be effected by means of a lever 58 having a short arm with a pawl 59 pivoted thereto and pressed into engagement with the teeth 22 by a spring 60. The other arm of the lever is connected by a rod 61 to a pedal 62 conveniently located below the bench 14 for engagement by the foot of an operator and as the pedal is depressed the lever advances the disc until the pawl engages an eccentrically adjustable stop 63 whereupon the pedal may be returned for the next engagement of the pawl with one of the teeth 22.

15 A hand stop or positioning device consisting of a locking pawl 64 may be pivoted on the base 27 and adapted to engage any one of the teeth 22 with a rod 65 connected at one end intermediate the ends of the pawl and having a grip or handle 66 at its other end. In this rod are notches 67 adapted to engage a fixed stop 68 so that by operating the handle the pawl 64 may be moved from a position free from the disc to a locking position engaging the disc and held in either position by one of the notches 67.

20 In order to open or release each gripper for the attachment of gut ribbons or plies each time the gripper head is rotated one step, an operating device is preferably connected with the pedal 62. This device comprises a holder 70 supported by an arm 71 extending from a bracket 72 at one side of the base 27. In the holder is a short shaft 73 extending endwise through the holder and having a nut 74 at one end for securing it in place. Mounted on the shaft and extending through the other end of the holder is a sleeve 75 having a sprocket 76 secured thereto and rotated in opposite directions by a chain 77. At one end of the chain is a spring 78 connected to some fixed part, as the base 27, and at the other end of the chain it is connected by a rod 79 with the pedal 62. Thus downward pressure on the pedal rotates the sleeve 75 in one direction and the action of the spring 78 returns the pedal to its upper position and rotates the sleeve in the other direction.

25 As the sleeve 75 is rotated it is moved endwise in the holder by means of a worm gear 80 secured thereto, the thread of which engages with a stud 81 projecting thereinto from the holder. At the inner end of the sleeve an arm 82 is secured which is rotated and moved endwise as the sleeve is rotated, the end of the arm having notches 83 and 84 at its edges and being 30 of a length to engage under each of the heads 51 of the gripping devices so that each depression of the pedal 62 moves the twisting head one step in advance and at the same time engages the arm 82 with the next gripper to be attached to the gut ribbons or plies, withdrawing the gripping rod 40 from its engagement with the end recess 42 and thus opening the slot 41 thereof for the free insertion, arrangement and disposition of the ply ribbons therein. The release of 35 pressure on the pedal 62 allows the spring 78 to return the gripping rod to gripping position and positions the arm 82 for engagement with the head of the next gripper. In its endwise movement the sleeve 75 will be projected on the shaft 73 and from the end of the holder the distance determined by the pitch of the thread of the worm gear 80.

40 The tension of the ribbons or plies may be easily adjusted and made practically the same in drawing them through the grippers and after

all of the grippers are thus attached the ribbons and plies will form an elongated cone as represented in Fig. 1, the difference in initial pressure being evident from the difference in sag of the plies which may then be adjusted so that all the ribbons or plies will have substantially the same pressure. At this time the plies may all be separately twisted by rotating the grippers by means of the gear 55 which is controlled by the motor 17. When the desired amount of twist has been given to each of the plies they are rounded, the tension is increased due to the shortening of the length of the ply on account of twisting, and each of the plies is of substantially the same length and tension.

The hook or loop at the other end of the string is then rotated to turn the hook or loop 11 in a relatively opposite direction, that is, if the plies are twisted counter-clockwise when looking from the end of the twisting head, the string is twisted in a clockwise direction so that the pull of all the plies will be toward the center of the string.

Twisting the string is then continued at intervals until the desired amount of turns have been made in the full length of the string, at 25 which time the ends of the plies or ribbons will be connected to the grippers in a short flat cone. The apex of this cone is then tightly engaged and the next operation is to remove or disengage all of the ribbons or plies from the gripper head. This is accomplished in a single operation and a loop is made of the ends of the ribbons or plies to keep them from untwisting.

The means for disengaging or releasing the grippers from the ribbons or plies comprises a plate 85 surrounding the bearing sleeve 25 and of a diameter slightly less than the distance between opposite rods 44 in the disc 20. Thus the outer periphery of the plate is of sufficient diameter to engage all of the heads 51 at the inside thereof so that by moving the plate 85 away from the disc 20 all of the rods 44 will be withdrawn from the outer ends of the grippers, thus releasing the gripped ends of the ribbons or plies. To accomplish this operation the central portion of the plate 85 is mounted upon a collar 86 slidable upon the sleeve 25 and engaged at its opposite sides by a yoke 87 in the form of a lever having a pivot 88 between its ends secured to the support 27 and its opposite end connected by a rod 89 with a pedal 90. The depression of this pedal causes the movement of the plate 85, engaging the heads 51 of all the grippers and moving them against the pressure of their springs 47 so that as soon as the pedal 90 is released all of the grippers will be returned to their gripping positions. The engagement of this plate 85 at the inner edges of the rods 44 does not affect or interfere with the operation of the releasing device which is operated by the other lever or pedal 62.

When a twisted string is thus disconnected from the gripper head the twisting of the string is complete, and the string is ready to be further processed or treated as desired, by smoothing, filling or polishing it, depending upon the surface or use for which it is intended.

A central hook 96 is threaded or otherwise connected to the end of the driving shaft 28 at the center of the spinning head, thus providing for the attachment of a central distinguishing core for the exclusive marking, and also providing means to which the gripper ends of the spun plies may be attached after removal from 75

the grippers for further twisting of the complete strings.

I claim:

1. An apparatus for making gut strings, comprising a rotatable head having gut ribbon and ply grippers spaced apart about the periphery of the head and individually rotatable therein for engagement at one end of the ribbons or plies, means for rotating the head and twisting together all the separately twisted plies, and means at their other ends for engaging all of the ribbons or plies for rotating and twisting them together at the same time.

2. In an apparatus for making twisted gut strings, a rotatable head having grippers spaced about the periphery and individually rotatable therein for engagement of gut ribbons or plies at one end thereof, means for rotating the grippers in the head and twisting the plies in one direction, means for rotating the head and with it the gripper twisted plies at one end, and means for engaging all of the ribbons or plies at their other ends for rotating them at the same time in the opposite direction.

3. In an apparatus for making twisted gut strings, a rotatable head having grippers spaced apart about the outer edge thereof adapted to engage the ends of gut ribbons and plies, means for rotating the grippers, and means for advancing the head step by step to bring each of the grippers successively into a predetermined position.

4. In an apparatus for making twisted gut strings, a rotatable head having means to advance it step by step in one direction, a plurality of grippers mounted about the periphery of the head, each gripper having a member movable therein for engaging one extremity of gut ribbons and separately rotatable therein for making a round ply of the ribbons.

5. In an apparatus for making twisted gut strings, a string-engaging head comprising a plurality of grippers disposed at spaced distances about the outer edge of the head, each gripper comprising relatively fixed and movable parts for engaging the ends of a plurality of gut ribbons, means for separately rotating the grippers and the head for uniting the gripper twisted ribbons, at the head end and means connected at the 50 other end of the ribbons for twisting them all together at the same time.

6. In a machine for twisting gut strings, means for engaging one end of all of the gut ribbons, a rotatable head at the other end having means for engaging groups of ribbons or plies, means for rotating the head in a step by step movement, means to rotate the ribbon engaging means for twisting them individually to form circular plies, means at the other ends of 60 the plies for twisting them all together, and means at the head of the ribbons for holding this end of the twisted plies in fixed position while the other end of the plies is being twisted.

7. In a machine for twisting gut strings, a rotatable head, a plurality of gut ribbon grippers rotatably mounted in the head, each gripper comprising a sleeve with a gear thereon, means in the head for engaging the gears of the grippers independently of the rotation of the head, the rotation of the head twisting together the separately twisted ribbons engaged by the grippers, and means at the other end of the ribbons for separately twisting them together.

8. In a machine for twisting gut strings, a

rotatable head, means about the outside of the head for releasably engaging gut string ribbons comprising a sleeve mounted in the head having a recess with a slot leading thereto at one end for inserting gut string ribbons, and a spring-pressed bolt movable in the sleeve to engage and grip ribbons disposed in the recess of the sleeve, the recess and bolt end being tapered.

9. In a machine for twisting gut strings, a rotatable head, means about the outside of the head for releasably engaging gut string ribbons comprising a sleeve mounted in the head having a recess at one end for receiving gut string ribbons, a spring pressed bolt movable in the sleeve to engage and grip ribbons disposed in the recess of the sleeve, means for rotating the head in a step by step movement, and means in connection with the gripper for withdrawing the bolt to open the recess in the sleeve for the admission of gut strings when the head is advanced in a step by step movement.

10. In a machine for twisting gut strings, a rotatable head, a plurality of gut ribbon grippers rotatably mounted in the head, each gripper comprising a rotatable sleeve and a spring-pressed bolt longitudinally movable in the sleeve, means in connection with the head for rotating the grippers independently of the rotation of the head, and means engageable with the bolts for moving them together longitudinally of the sleeves for releasing gut ribbon connections therewith.

11. In a machine for twisting gut strings, a gut ribbon gripper and ply twister comprising a sleeve having a gear thereon for rotating it, a recess in the sleeve with a slot opening thereto from one end for inserting gut ribbons therein, a bolt longitudinally movable in the sleeve to engage and grip gut ribbons threaded through the slot and located in the recess, and a spring

for pressing the bolt in engagement with the ribbons.

12. A structure in accordance with claim 11 in which the end of the bolt is tapered and the inner end of the sleeve is correspondingly tapered to fit the bolt at the recessed end of the sleeve into which the bolt is pressed by the spring thereof.

13. A structure in accordance with claim 11 in which the recess near one end of the sleeve has a slot extending therefrom to the end, and an opposite bayonet locking recess, and the bolt has a stud extending therefrom into the recess adapted to be engaged with the bayonet locking notch against the pressure of the spring.

14. A gut string gripper in accordance with claim 11 in which the bolt has a projection into the recess for limiting relative rotation of the bolt with respect to the sleeve, and the end of the bolt opposite the recess in the sleeve has a collar attached thereto for moving the bolt rearwardly against the pressure of the spring between the bolt and its sleeve.

15. In a machine for twisting gut strings, a rotatable head, a plurality of gut ribbon grippers 25 rotatably mounted about the outer edge of the head, means for advancing the head in a step by step movement, each gripper comprising a sleeve rotatable in the head, and a spring-pressed stem longitudinally movable in the sleeve 30 with an engageable collar at one end of the bolt outside of the sleeve, means for engaging the collars of successive bolts as the head is rotated in a step by step movement for moving each bolt against the tension of its spring, and means engageable with all of the collars at the same time 35 for moving them against the tension of their springs to release gut ribbons from the other ends of the grippers.

HAROLD W. ROBERTS.
